UNITED STATES PATENT OFFICE.

CHARLES ALDEN, OF NEWBURG, NEW YORK.

IMPROVED APPARATUS FOR DRYING AND EVAPORATING.

Specification forming part of Letters Patent No. 100,835, dated March 15, 1870.

To all whom it may concern:

Be it known that I, CHARLES ALDEN, of Newburg, in the county of Orange and State of New York, have invented a new and Improved Evaporator; and I do hereby declare the following to be a full, clear, and exact description thereof, which will enable those skilled in the art to make and use the same, reference being had to the accompanying drawing forming part of this specification, in which drawing—

Figure 1 represents a transverse vertical section of this invention. Fig. 2 is a longitudinal vertical section of the same. Fig. 3 is a horizontal section of the same.

Similar letters indicate corresponding parts.

This invention consists in the arrangement of a series of platforms attached to endless chains, and receiving a rising-and-falling motion in a trunk or chamber supplied with a current or currents of hot or cold air in such a manner that if said platforms are loaded with any material containing moisture such moisture is rapidly evaporated with little trouble or expense. On one or more sides of the trunk are air-chambers provided with nozzles to throw currents of air over or between the platforms. Said platforms are supported by fingers projecting from the endless chains, and so arranged that each platform, after having been carried to the desired distance, is deposited upon a conveyer and thereby removed from the trunk.

In the drawing, the letters A A designate the side walls of the trunk, which form the bearings for the shafts B B, which carry the chain-wheels C C and the endless chains D D. These chains are provided with fingers E, which form the supports for the platforms F. Said platforms are perforated with small holes to allow a free circulation of the air, and they are held in position in one direction by the sides of the trunk and in the other by the chains. The motion of the chains D is derived from the driving-shaft L, which is driven either by a hand-crank, M, or by a pulley, M, said shaft being connected with the chain-shafts B B by means of gear-wheels K and a stop-pawl, Z,

which engages with a ratchet-wheel, Y, mounted on the shaft L, serves to arrest the chains at any desired point. The chain-wheels C C at the bottom of the trunk are driven simply by the chains, and if the trunk is high the chains are steadied by intermediate guide-rollers. Each of the platforms on reaching the bottom of the trunk is deposited upon the conveyer N, which receives motion by a pulley, O, and small belt-wheels o o', and by this conveyer the successive platforms are carried out of the trunk, so that they can be readily removed and again introduced at the top of the trunk. On the sides of the trunk are arranged two air-chambers, P P, which are supplied with hot or cold air from below, and which are provided with nozzles p for the discharge of the air. By these means currents of hot or cold air thrown over or between the platforms, and these currents are regulated by dampers r. If hot air is used, suitable thermometers t may be applied in boxes S, attached to the sides of the trunk, to indicate the temperature of the air in the trunk. Suitable flues Q Q may be applied to introduce currents of cold air into the trunk to regulate the temperature, if desired.

The articles or materials from which the moisture is to be evaporated are placed upon the platforms, and, as said platforms move slowly down through the trunk, the currents of air passing over or through said articles carry off the moisture with great rapidity.

This apparatus can be used with great advantage for evaporating cane-juice or other liquids of a similar nature, or for evaporating the moisture contained in wool, cotton, grain, or other solid materials.

What I claim as new, and desire to secure by Letters Patent, is—

1. The arrangement of a series of platforms attached to endless chains, and receiving a rising-or-falling motion in a trunk or chamber supplied with a current or currents of hot or cold air, substantially in the manner shown and described.

2. The arrangement of an air chamber on one or more sides of the trunk, said air-cham-

bers being provided with nozzles to throw currents of air over or between the platforms, substantially as set forth.

3. The arrangement of fingers projecting from the endless chains, and capable of supporting the platforms during their rise or fall, and of depositing the same automatically at the bottom of the trunk, substantially as described.

4. The arrangement of a conveyer, substantially as described, in combination with the platform and with the endless chains and their fingers, so as to remove said platforms from the bottom of the trunk.

CHARLES ALDEN.
